(57) **CLAIM**

The ornamental design for a pill box, as shown and described.

DESCRIPTION

FIG. 1 is a front view of an ornamental design for a pill box showing my new design;

FIG. 2 is a rear view of the pill box;

FIG. 3 is a left side view of the pill box;

FIG. 4 is a right side view of the pill box;

FIG. 5 is a top view of the pill box;

FIG. 6 is a bottom view of the pill box;

FIG. 7 is a front and right side perspective view of the pill box;

FIG. 8 is a rear and left side perspective view of the pill box; and,

FIG. 9 is a front and right side perspective view of the pill box in its open state.

The broken lines in the figures are for environmental purposes only and form no part of the claimed design.

Any shading and cross-hatching are not features of the design but are utilized to illustrate the surface contours of the pill box in the drawings.

1 Claim, 9 Drawing Sheets
